(57) **CLAIM**

The ornamental design for an upper body garment, as shown and described.

DESCRIPTION

FIG. 1 is a perspective view of the upper body garment showing my new design;

FIG. 2 is a front plan view thereof;

FIG. 3 is a rear plan view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the upper body garment with the releasable opening in an open position.

The broken lines illustrate environmental structure and form no part of the claimed design.
